UNITED STATES PATENT OFFICE.

WILLIAM R. WEBSTER, OF BRIDGEPORT, CONNECTICUT.

METHOD OF AND MEANS FOR EXTRUDING BRASS AND LIKE MATERIAL.

Application filed June 6, 1922. Serial No. 566,214.

To all whom it may concern:

Be it known that I, WILLIAM R. WEBSTER, a citizen of the United States, residing in Bridgeport, county of Fairfield, and State of Connecticut, have invented certain new and useful Improvements in Methods of and Means for Extruding Brass and like Material, of which the following is a full, clear, and exact description.

10 This invention relates to the extrusion of metal and more particularly to an extrusion process in which a heated metal billet is placed in a suitable container or receiver and extruded therefrom through a die.

15 It is common practice in the extrusion of metal to accomplish the extrusion process by means of a machine provided with a movable extrusion ram which enters one end of the billet container and is moved there-

20 through to extrude the metal through the other end. The die is placed against the end of the container through which the metal is extruded and is held thereagainst by a suitable die backing, the die and con-

25 tainer normally being held in a stationary position while the movable ram is forced through the container to extrude the metal through the die. It will thus be apparent that in this process a relative motion is

30 brought about between the die and container on the one hand and the movable ram on the other, the two former elements normally remaining fixed while the latter is moved.

35 It is found that when a brass billet is extruded by the process outlined above or processes similar thereto, the last portion of the rod (assuming that a rod is being extruded through the die) to leave the die

40 contains a characteristic defect which is practically always present. This defect is normally present in perhaps the last 25 to 30 per cent of the extruded rod, so that a considerable loss is entailed as this portion

45 of the rod is not usable, and, as stated above, comprises one-fourth or more of the extruded length. This defect appears as a flaw or "pipe" in the inner part of the extruded product, consisting usually of foreign material distributed in the general form of a tube, approximately co-axial with the rod.

The occurrence of this defect, as explained in my application, Serial No. 508,669, filed

55 October 19, 1921, is thought to be due to

the fact that the outer skin of the billet becomes chilled by contact with the periphery of the container bore and flows less readily than the inner part of the billet and consequently advances toward the billet axis and is carried forward and inward by the flow of the metal through the die thus forming the "pipe". As also explained in my prior application, this defect may be largely eliminated if the extrusion process is carried out by producing a movement of the die relatively to the billet container and ram instead of by the usual process outlined above.

It has been discovered, however, that when a metal billet is extruded in accordance with the process described in my prior application, certain defects will under some conditions appear on the exterior surface of the extruded rod. This is apt to be the case where the billet to be extruded has a poor or imperfect surface. In order, therefore, to permit the use of a billet of this character and still to avoid the "pipe" or like defects found in rods extruded by former methods, the present invention contemplates the extrusion of a portion of the billet (usually the first portion) by the former process, wherein the ram is moved relatively to the billet container and die, and the extrusion of the remainder by the process outlined in my previous application, wherein the ram and billet container are both moved relatively to the die.

One object of my invention, therefore, is to overcome the disadvantages formerly encountered, by the provision of a new and improved process of extruding metal such that the extruded work will not contain defects or flaws even where a billet having a noticeably imperfect surface is used.

Another object is to provide a new and improved method of extruding a metal billet such that practically the entire billet may be extruded without the formation of objectionable internal or external flaws or defects in the extruded work.

Another object is to provide an improved and commercially practicable process of extruding metal wherein during a part of the operation the billet is moved relatively to the billet container and during another part of the operation the billet and billet container are moved together relatively to the die, these two phases being so coordinated

as to produce the most satisfactory results from a manufacturing standpoint.

A still further object of my invention is to provide a new and improved extrusion machine for carrying out the process outlined above. More specifically the invention contemplates a simple, efficient machine comprising means designed for first producing a relative movement between the ram and billet container and thereafter producing a relative movement between the die on the one hand and the billet container and ram on the other.

To these and other ends the invention consists in the novel features and combinations of parts to be hereinafter described and claimed.

In the accompanying drawings:

Fig. 1 is a side elevational view of an extrusion machine for carrying out my improved process, the parts being in position to receive a billet to be extruded;

Fig. 2 is a sectional view on line 2—2 of Fig. 1;

Fig. 3 is a top plan view of the machine, some parts being shown in section;

Fig. 4 is a longitudinal sectional view of the machine, the parts being shown in the position occupied at the beginning of the extrusion operation;

Fig. 5 is a transverse sectional view on line 5—5 of Fig. 4;

Fig. 6 is a sectional view on line 6—6 of Fig. 4;

Fig. 7 is a sectional view on line 7—7 of Fig. 4;

Fig. 8 is a fragmentary longitudinal sectional view showing the position occupied by the parts prior to the positioning of the billet in the container; and

Figs. 9 to 14 are views similar to Fig. 8 showing different stages in the extrusion operation.

As has been stated above, the present processes for extruding brass and similar metals are very wasteful, as the scrapping of a quarter or more of the extruded work is ordinarily unavoidable on account of the defects appearing therein. As a result of attempts to prevent this waste, I have discovered that when a part of the extrusion operation is accomplished by the movement of the extrusion ram into the billet container, and the remainder produced by a relative movement between the container and the die, substantially the entire billet may be extruded without any defect appearing in the extruded work. By means of this process the chilled exterior surface of the billet, which in extrusion methods in use at the present time forms a defect in the extruded rod, remains in the small stump or stub which is left in the container at the end of the operation. It will be apparent that a very great saving is thereby achieved.

The machine which I have selected to illustrate the carrying out of my improved method, comprises end frames 10 and 11, which may be supported upon suitable base blocks 12 and 13 and connected by tie rods 14, 15 and 16, three in number as shown. The frame 10 is provided with a fluid cylinder 17 in which is mounted a piston 18 designed to furnish the power for the extrusion operation. The pressure fluid may be admitted to the cylinder 17 through the pipe 19.

To the forward end of the piston 18 is secured a cross-head or carriage 20 provided with bearings 21, 22 and 23 adapted to engage and slidably mount the carriage upon the tie rods 14, 15 and 16. As shown, the carriage is provided with a reduced projecting portion 24 at its rear side designed to enter the bore 25 of the piston to suitably connect the two for movement together. At the front of the cross-head is mounted a plunger or ram 26 adapted to enter the receiving bore 27 of the billet container 28. This ram or plunger is preferably slightly greater in length than the receiving bore 27 so that after the extrusion process has been completed, the remaining stump or sprue may be expelled by relative movement of the plunger and container.

The billet container 28 is carried by and mounted within a movable carriage 29 which is slidably mounted upon the two lower tie rods 15 and 16 by means of bearings 30 and 31. To the carriage 29 are connected a pair of rods 32 and 33, these rods being continuations of two pistons 34 mounted in cylinders 35 and 36 carried by the frame 10 upon opposite sides of the cylinder 17. The cylinders 35 and 36 are provided with fluid supply pipes 37, 38, 39 and 40 for admitting fluid pressure upon either side of the pistons 34 in order to drive the pistons in opposite directions. It will be apparent that by proper control of the fluid pressure through these pipes, the pistons, together with the container carriage, and container, may be moved in either direction lengthwise of the tie rods 15 and 16.

Upon the end frame 11 is mounted a frame or standard 41 having an arm 43 which carries a vertically disposed cylinder 44 having pressure supply pipes 45 and 46 to admit fluid pressure upon either side of a piston 47. To the piston 47 is connected a rod 48 extending downwardly toward the tie rod 14. A pair of bell crank levers 49 and 50 are mounted upon the tie rod 14 by the provision of collars 51 and 52 surrounding this rod, the upper arms 53 and 54 of these levers being connected to the rod 48 for operation thereby by a pair of toggle links 55 and 56 pivoted to the rod at their upper ends and to the arms 53 and 54 at their lower ends. The other arms 57 and 58 of the bell crank levers project downwardly

from the tie rod 14 and carry upon their lower ends a pair of cooperating semi-cylindrical spacing jaws 59 and 60 which cooperate when in operative position to form a cylindrical spacing collar about a hollow ram 64 to be hereinafter described. Upon referring to Figs. 1, 4 and 7, it will be apparent that when pressure fluid is admitted below the piston 47 and the latter moved to the upper end of the cylinder 44, the toggle links 55 and 56 will assume a vertical position, as shown in Fig. 1, and spread the spacing jaws 59 and 60, as shown in that figure, the jaws being swung away from the ram. On the other hand, when pressure is admitted above the piston 47 and the latter forced downwardly, the toggle members will be urged toward a horizontal position, as shown in Figs. 4 and 7 and the spacing jaws will be moved to embrace the ram.

In the end frame 11 is provided a longitudinally disposed opening or bore 61, which receives a reduced rearwardly projecting cylindrical portion 62 of a ram carrying head 63 carrying upon its opposite side the ram 64. Upon the end of the ram is provided a die seat 65 in which is mounted a die 66 having a bore 67 through which the metal billet is adapted to be extruded. In this instance the die carrying ram is preferably provided with a longitudinal bore 68 through which the extruded work may pass.

Although it may not always be necessary in the carrying out of my improved process, I prefer to provide spacing blocks to surround the ram 26 in order to limit its movement toward the container 28. For this purpose a frame or standard 70 is mounted upon the carriage 20, the standard consisting of a pair of spaced legs 71 and 72 extending upwardly upon either side of the tie rod 14 and converging to form an arm 73 upon which is mounted a vertically disposed cylinder 74 having pressure supply pipes 75 and 76 to admit fluid pressure upon either side of a piston 77. To the piston 77 is connected a rod 78 extending downwardly through the end of the cylinder. A pair of bell crank levers 79 and 80 are mounted upon the tie rod 14 by the provision of collars 81 and 82 surrounding this rod, the upper arms 83 and 84 of these levers being connected to the rod 78 for operation thereby by a pair of toggle links 85 and 86 pivoted to the rod at their upper ends and to the arms 83 and 84 at their lower ends. The remaining arms 87 and 88 of the bell crank levers project downwardly and carry upon their lower ends a pair of cooperating semi-cylindrical spacing jaws 89 and 90, which cooperate when in operative position to form a cylindrical spacing collar about the plunger or ram 26. The operation of these

spacing jaws by means of the piston 77 is precisely as explained in connection with the spacing jaws 59 and 60.

The operation of my device is as follows: Assuming that the parts are in the position shown in Figs. 1 and 8, the billet container and plunger 26 both being in their extreme right hand positions, as found in these figures, a billet 91 is placed opposite the container bore 27. Fluid pressure is then admitted through pipes 37 and 38 to move the billet container to the left so that the billet may be received in the bore thereof, as shown in Fig. 9. By the admission of fluid pressure in the pipe 45, the piston 47 is moved downwardly, as shown in Fig. 4, and the spacing collars 59 and 60 are moved to embrace the hollow die carrying ram so as to limit the movement of the billet container toward the left. The width of the spacing collars, as shown, is slightly less than the length of the hollow die carrying ram, so that this ram will enter the container bore to some extent, although the proportions may be varied as desired. It will be obvious, of course, that the length of this ram will depend upon the proportion of the entire process which is to be carried out during a relative movement of the container and die. The parts then being in the position shown in Fig. 9, the extrusion operation is begun by the admission of fluid pressure to the cylinder 17 and the carriage 20 is moved to the left, carrying with it the plunger 26 and the frame 70. This operation is continued until as much of the billet is extruded as it is desired to extrude by the movement of the ram relatively to the billet container, as shown in Fig. 10. By the admission of fluid pressure to the pipes 46 and 75, the spacing jaws 59 and 60 are then withdrawn from their position embracing the ram 64 and the spacing collars 89 and 90 are brought into position about the plunger 26 between the carriage 20 and the billet container 28, as shown in Fig. 11. Pressure is again admitted to the cylinder 17 and the remainder of the billet extruded, as shown in Fig. 12. During this part of the process the billet container and plunger have moved together relatively to the die carrying ram 64, the container being pushed forward with the plunger by the spacing jaws 89 and 90. The die carrying ram during this stage of the process enters the bore of the billet container, the other end of which is sealed by the plunger 26 and the remainder of the billet is extruded through the opening in the die and the hollow die carrying ram, as shown in Fig. 12, and the movement is continued until practically the entire billet is extruded, a small stump 92 remaining in the container. The spacing jaws 89 and 90 are now moved upwardly into inopera-

tive position and the container 28 is moved toward the right by means of the pistons 32 and 33, as shown in Fig. 13. As the plunger 26 remains stationary during this 5 part of the operation, the stump 92 is expelled from the container.

The motion of the container is now continued toward the right by means of the piston rods 32 and 33, the container carrying with it the plunger 26 and cross-head 20 to the extreme right hand position shown in Fig. 14. The stump 92 may now be severed from the extruded rod immediately adjacent the face of the die and the parts 10 are in position to receive another billet, as 15 shown in Fig. 8.

As previously indicated, it will not always be necessary, when the parts are in the position shown in Fig. 10, and it is desired to 20 move the ram and billet container together thereafter, to throw the spacing jaws 89 and 90 into operative position between the cross-head 20 and the container, as the movement of the plunger 26 after the spacing blocks 23 59 and 60 have been withdrawn will carry the container over the hollow die carrying ram due to the frictional resistance of the billet against the periphery of the container bore. It will be understood, therefore, that 30 my improved extrusion process may be accomplished either with or without the use of the spacing blocks 89 and 90.

I have found that in my improved process the interior flaw or "pipe" encountered in 35 the product resulting from the process which has heretofore been common practice is practically eliminated and that the exterior or surface defects encountered under certain conditions in the method described 40 in my previous application above referred to are also completely avoided. It will be obvious, therefore, that a great saving is accomplished by the present method of extrusion and a product is produced which is 45 practically free from defects or flaws. While the proportion of the billet which is extruded by the first part of the present process, that is by the movement of the ram relatively to the billet container, may be 50 varied as desired, in practice I have found it expedient to extrude approximately two-thirds of the billet in this manner before the spacing jaws 59 and 60 are removed. In other words, the part which is extruded 55 during the first part of the present process is approximately, that part of the billet which could be extruded in the ordinary way without the appearance of defects in the extruded element. 60 It will, of course, be obvious that the extrusion is produced by a relative movement between the die on the one hand and the plunger on the other, and while in the device shown in the drawings the die is represented as a fixed element and the plunger 65

as a movable element, it may sometimes be found expedient to arrange the structure so that the die is movable and the plunger remains stationary. The same relative movement and, therefore, the same result 70 could be accomplished in this manner.

While I have shown and described my improved method and machine as applied to extrusion of brass rods, it will be apparent that I do not intend to limit myself to this 75 particular use of my invention, which may be varied in many details without departing from the spirit of the invention or from the scope of the appended claims. My improved method is, of course, equally applicable to 80 the extrusion of copper alloys other than brass and other metals that are placed in suitable condition for extruding by the application of heat to the billet. It will be obvious that my invention is not limited 85 to a device employing a die seated in a recess in the ram, as a suitable die may merely be placed between the ram and the billet or a hollow ram alone may be used without the 90 employment of a separate die, the die being 90 constituted in effect by the end of the ram.

What I claim is:

1. In a metal extruding machine, a frame, a billet container movably mounted thereon, means to limit the movement of the billet 95 container in one direction, said means being capable of being rendered inoperative to permit movement of the container.

2. A metal extruding machine comprising a movable billet container, means for extruding a billet therefrom, and movably mounted means to limit the movement of the billet container in one direction. 100

3. A metal extruding machine comprising a movable billet container and means for extruding a billet therefrom, means to limit the movement of the billet container in one direction, and means to move said limiting 105 means to inoperative position.

4. A metal extruding machine including 110 a pair of end frames, tie rods connecting the end frames, a billet container movably mounted on said tie rods, and a stop movable in and out of position between one face of the billet container and the adjacent 115 end frame to limit the movement of the container toward the frame.

5. A metal extruding machine including a billet container, a ram for extruding a billet therefrom, stop means movable to 120 position to prevent movement of the container, and means to move said stop means to inoperative position to permit the container to be moved by the ram.

6. An extrusion machine including a billet 125 container, and means for extruding a portion of a billet therefrom while permitting relative movement between the billet and the container and extruding the remainder 130 of the billet therefrom by preventing rela-

tive movement between the billet and the container.

7. An extrusion machine including a billet container, a die cooperating therewith, means to extrude a portion of a billet through the die while preventing relative movement between the container and die and to hold the remainder of the billet within the container while producing relative movement between the container and die to extrude said billet remainder.

8. An extrusion machine including a billet container having a billet receiving bore, a plunger adapted to enter one end of the bore, a die adapted to enter the opposite end of the bore, and means for producing relative movement between the plunger and container during a part of the extrusion process and producing relative movement between the die and container for the remainder of the extrusion process.

9. An extrusion machine including a billet container having a billet receiving bore, a plunger adapted to enter one end of the bore, a die adapted to enter the opposite end of the bore, and means for producing relative movement between the plunger and container during the first part of the extrusion process and producing relative movement between the die and container during the last part of the extrusion process.

10. An extrusion machine including a billet container having a billet receiving bore, a plunger adapted to enter one end of the bore, a hollow die carrying ram adapted to enter the opposite end of the bore, and means to cause said plunger to enter the bore of the billet container during a part of the extrusion operation and to thrust the die carrying ram into the bore of the billet container during another part of the extrusion operation.

11. An extrusion machine including a billet container, a plunger and die cooperating therewith, means for producing relative movement between the plunger and die to extrude the billet, and means to cause relative movement between the container and plunger during a part of the operation and between the container and die during another part of the operation.

12. An extrusion machine comprising a billet container, a plunger and die cooperating therewith, means to move the plunger relatively to the die to extrude a billet therethrough, and means to cause relative movement between the container and plunger during a part of the extrusion process and to cause the container and plunger to move together during the remainder of the extrusion process.

13. An extrusion machine comprising a billet container, a die cooperating with one end thereof, a plunger, means to move said plunger through the billet container toward

the die during a part of the extrusion process and to move the billet container and plunger as a unit toward the die during the remainder of the extrusion process.

14. An extruding machine comprising a billet container, a plunger and die cooperating therewith, means to move the plunger through the billet container toward the die to extrude a billet through the latter and means to limit the movement of the plunger toward the billet container.

15. An extrusion machine comprising a billet container, a plunger and die cooperating therewith, means to extrude a portion of a billet through the die while limiting the movement between the container and die, and for extruding the remainder of the billet while limiting movement between the plunger and the container.

16. In an extrusion machine, a billet container, a plunger and die cooperating therewith and means for moving both said plunger and die a substantial distance into the bore of the billet container to complete the extrusion of a billet through the die.

17. An extruding machine including a pair of end frames, tie rods connecting the end frames, a billet container movably mounted on the tie rods, stop mechanism carried by one of the tie rods and adapted to be moved into position between one face of the billet container and the adjacent end frame.

18. An extrusion machine comprising a billet container, a plunger designed to enter the container bore, and stop mechanism to limit the entry of the plunger within the bore, said stop mechanism being designed to permit the plunger to move at least half way through the container.

19. The method of extruding metal which consists in placing it in a billet container and extruding it through a die while producing relative movement between the billet and container during a part of the extrusion operation and preventing such movement during another part of the extrusion operation.

20. The method of extruding a heated metal billet which comprises inserting it in a bore in a suitable container, positioning a die at one end of the billet and extruding a portion of it through the die by producing relative movement between the billet and the container and extruding the remainder while holding the billet against movement in the container.

21. The method of extruding a heated billet which comprises inserting it in a bore in a suitable container and moving it there through toward a die for a part of the extrusion process and producing a relative advancing movement between the die and container for another part of the extrusion process.

22. A method of extruding a heated metal billet which comprises inserting it in a bore in a suitable container, positioning a plunger at one end of the bore and a die at the other end of the bore advancing the plunger into the container for a part of the extrusion process and advancing the die into the container during the remainder of the process.
23. The method of extruding a heated metal billet which comprises placing the billet in a container and advancing a plunger into one end of the container bore and a die into the opposite end.
24. The method of extruding a heated metal billet which comprises inserting it in a suitable container and extruding the billet through a die by advancing a plunger part way through a container bore and a die into the container bore for substantially the remainder of the length thereof.
25. The method of extruding a heated metal billet which comprises placing the billet in the bore of a suitable container and advancing a plunger and a die into opposite ends of the container bore, respectively.
26. The method of extruding a heated metal billet which comprises placing the billet in a suitable container and extruding it through a die while preventing "pipe" and surface defects in the extruded work.
27. In an extrusion machine, a movably mounted billet container and a removable stop for limiting movement of said container.
28. An extrusion machine comprising a billet container, a plunger and die cooperating therewith, means to extrude a portion of the billet through the die while limiting movement between the container and die and for extruding another portion of the billet while permitting movement between the container and die.
29. An extrusion machine comprising a billet container, a plunger movable therethrough to extrude a billet contained therein, and means to limit the extruding movement of the plunger through the container.
30. An extrusion machine comprising a billet container, a plunger and die cooperating therewith, said plunger being movable through the bore of the container, means to limit the movement of the container during an extruding movement of the plunger through the container bore, means to limit the extruding movement of the plunger, and means to withdraw the first named limiting means from operative position and permit movement of the container.
31. The method of extruding a heated metal billet, which comprises inserting it in the bore of a suitable container, and extruding more than half of the billet through a die by advancing a plunger into one end of the container bore, and extruding the remainder of the billet by advancing the die into the opposite end of the container bore.
32. The method of extruding a heated metal billet, which comprises placing the hot billet in a container, and extruding a portion of it by thrusting a plunger into the container bore against one end of the billet, and extruding another portion by forcing into the billet a hollow ram.
33. The method of extruding a heated metal billet, which comprises placing a hot billet in a container and extruding a portion of it through a die while preventing relative movement between the container and die, extruding a further portion of the billet while preventing relative movement between the container and the unextruded part of the billet, and then producing relative movement between the container and stump to strip the latter.
34. The method of extruding a heated metal billet, which comprises placing the billet in a suitable container, and extruding more than half of it therefrom by a movement of the billet through the container, and then extruding a further portion of the billet while preventing relative movement of the billet and container.

In witness whereof, I have hereunto set my hand this 2nd of June, 1922.

WILLIAM R. WEBSTER
